ATTORNEY

UNITED STATES PATENT OFFICE.

ARTHUR HOLMES, OF CANTON, OHIO, ASSIGNOR TO THE HOLMES AUTOMOBILE COMPANY, OF CANTON, OHIO, A CORPORATION OF OHIO.

MANIFOLD.

1,375,910.

Specification of Letters Patent. Patented Apr. 26, 1921.

Application filed April 28, 1920. Serial No. 377,360.

To all whom it may concern:

Be it known that I, ARTHUR HOLMES, of Canton, in the county of Stark, in the State of Ohio, have invented new and useful Improvements in Manifolds, of which the following, taken in connection with the accompanying drawings, is a full, clear, and exact description.

This invention relates to certain improvements in internal combustion engines and pertains more particularly to an inlet manifold for multi-cylinder engines of the type named and reference is hereby made to my co-pending application, Serial Number 207,868, filed December 19, 1917, and containing the broad claims to a manifold embodying the principles of construction utilized in the present disclosures.

With the constantly decreasing volatility of the gasoline now being supplied for use in internal combustion engines, and particularly in cold weather until the motor warms up, it has been a more and more difficult problem to prevent one or more cylinders from getting more fuel in proportion to air as compared to other cylinders of the same engine using the same carburetor. This trouble is caused by the fact that the mixture traveling through the inlet manifold is not altogether a homogeneous gas, but partly a mechanical mixture of particles of unvaporized fuel, vaporized fuel and air.

It is easy to distribute the air and truly vaporized fuel, but the particles of unvaporized fuel, having a greater specific gravity than the former, present a different problem due to the tendency to throw such particles to one side at any bend in the passage and particularly under such condition as the turning of a corner in the inlet manifold, where inertia becomes effective, the unvaporized gas or liquid going in a straight line while the air and gas turn the corner without difficulty.

This fault in previous inlet manifolds makes it impossible to adjust the mixture at its origin in the carburetor so as to give the proper mixture in all cylinders, resulting in non-uniform operation and loss of power over what the engine would give with proper distribution of fuel, and in a tendency to soot the spark plugs and form carbon on the walls of the cylinders getting the rich mixture resulting in misfiring and

other effects detrimental to the running qualities of the engine.

Designers have, in the past, made many attempts to correct this fault in the distribution of the mixture. One way has been to apply heat to the mixture at the carburetor and during its passage to the various cylinders in an attempt to thoroughly vaporize the fuel and prevent condensation on its way to the cylinder. The difficulty with this method is that the amount of heat necessary to produce the required results is so great that it reduces the volumetric efficiency of the engine and often results in cracking, or disintegrating the fuel. Other attempts have been made along the line of making the path of the gases to the various cylinders equal in length but designers of this type of manifold failed to take into consideration the fact that at the bends in the passages fuel is thrown out by centrifugal force and due to the shape of the manifold is thrown into one or more cylinders out of proportion to the remaining cylinders.

This invention takes into consideration the inertia of the free fuel and takes advantage of this inertia to obtain equal qualitative distribution of the mixture with the result that the engine is exceedingly smooth in operation at all times, the spark plugs are not fouled, and misfiring and other detrimental results are avoided.

Other objects and advantages of the invention relate to the details of construction and operation as will more fully appear from the following description, taken in connection with the accompanying drawings, in which:—

Figure 1 is a sectional view of the manifold.

Fig. 2 is an elevation of the same.

The drawings illustrate a manifold designed specifically for an engine comprising four (4) cylinders in a row, adapted to be supplied from a single fuel source.

As shown, this particular embodiment of my invention consists of a main conduit —1— having at substantially its central point a carburetor branch —2— through which the fuel is supplied to the main conduit —1—, the latter conduit acting to effect an equal qualitative distribution of fuel to the branch conduits —3—, —4—, —5— and —6—. Preferably, these branch con-

duits are of arcuate form and merge symmetrically into the main conduit and their outlet ends are in communication with respective engine cylinders, as for instance, 5 through openings in the wall —7— of the cylinders. Obviously, the cylinders may be of an individual character, or may be cast *en-bloc*.

In order to effect equal qualitative distribution of fuel to all of the cylinders through 10 respective branch conduits the central portion —8— of the main conduit is offset, toward the outlet of the branch conduits a distance substantially equal to one-half the 15 diameter of the main conduit, such off-set portion being so constructed and arranged that the division lines or Y's —9— and —10— at the junction of the branch conduits —4— and —5— with the main conduit extend partially across the center off-set portion —8— of said conduit, and as shown, extend substantially half-way across the off-set portion to form deflecting surfaces —11— and —12—. This construction 20 does not reduce the diameter of the main conduit beyond the said lines of division or Y's.

The object of this construction will be readily understood: When the cylinder in 30 communication with branch —3— draws its charge, a portion of the fuel in passing the Y —9— will be thrown by its inertia into branch —4— due to the position of the deflecting surface —11—, practically all of the 35 air and vapor going to the branch —3—. The fuel thus deposited in branch —4— will remain there until the cylinder in communication with that branch draws its charge. When this takes place a portion of the free 40 fuel will be thrown by its inertia into the branch —3—, the amount in each instance depending upon the position of the division or Y —9—, and as this division line is practically in line with the center of the off-set portion —8— of the main conduit, the 45 amount of free fuel thrown into branch —3— when the cylinder in communication with branch —4— is drawing its charge, and the amount of free fuel drawn into branch —4— when the cylinder in communication 50 with branch —3— draws its charge should be substantially equal, and are in practice found to be substantially equal, thus effecting an equal qualitative distribution of fuel to these cylinders.

The operation in connection with branches

—5— and —6— is the same as that just described, and as branch —3— is of substantially the same form and construction as branch —6— and branch —4— is in substantially the same form and construction as branch —5—, a substantially equal qualitative distribution of fuel to all the cylinders is affected.

Although I have shown and described a 65 specific construction as illustrative of my invention, it will be obvious that changes in details of form and construction may be made without departing from the invention as set forth in the appended claims. 70

What I claim is:

1. An inlet manifold for multi-cylinder engines consisting of four cylinders arranged in a row and adapted to be supplied from one fuel source, comprising a main conduit and four branch conduits in communication therewith, a carbureter branch connected to substantially the central portion of the main conduit, said main conduit having its central portion off-set in a direction toward the outlet of the said branches a distance approximately one-half the diameter of said main conduit, the line of division between the main conduit and the branches for the second and third cylinders being substantially on the extended center line of said off-set central portion of the main conduit, said line of division being adapted to give substantially equal qualitative distribution of fuel to all the cylinders. 80

2. An inlet manifold for multi-cylinder engines consisting of four cylinders arranged in a row and adapted to be supplied from one fuel source consisting of a main conduit and four branch conduits in communication with the main conduit, said main conduit having its central portion off-set toward the outlet of the said branch conduits, a carbureter conduit connected to said central off-set portion of the main conduit 95 and the two intermediate branch conduits connected to said central off-set portion of the main conduit and having their outer walls constituting deflecting surfaces extending partially across the off-set central 100 portion of said main conduit. 105

In witness whereof I have hereunto set my hand this 20th day of April 1920.

ARTHUR HOLMES.
